C. WARES

SLIDING PAD

Filed Nov. 14, 1922

FIG. 1.

FIG. 2

FIG. 3.

Inventor
Clyde Wares,
William C. Linton.
Attorney

UNITED STATES PATENT OFFICE.

CLYDE WARES, OF HANFORD, CALIFORNIA.

SLIDING PAD.

Application filed November 14, 1922. Serial No. 600,918.

To all whom it may concern:

Be it known that I, CLYDE WARES, a citizen of the United States of America, residing at Hanford, in the county of Kings and 5 State of California, have invented certain new and useful Improvements in Sliding Pads; and I do hereby declare that the following is a full, clear, concise, and exact 10 description of the invention, such as will enable others skilled in the art to which it app- 15 pertains to make and use the same.

This invention relates to improvements in sliding pads for use by baseball players, hav- 20 ing for an object to provide a sliding pad so 25 constructed as to effectually protect or shield a wearer from abrasions, commonly termed "strawberries," upon those portions of the hips or legs contacting with the ground dur- 30 ing sliding to bases while participating in the playing of a game.

It is likewise an object of the invention to 35 provide a sliding pad of the character men- 40 tioned, the arrangement of which is such as will permit a portion thereof to at all times 45 cover and shield the hip or leg adjacent 50 which it is worn, irrespective of the move- 55 ment of the body during "sliding," as in the 60 irregular course taken by it when a player 65 executes the so-called "hook" or "fade-away" 70 slide.

Other objects will be in part obvious and 75 in part pointed out hereinafter.

In order that the invention and its mode 80 of operation may be readily understood by 85 persons skilled in the art, I have in the 90 accompanying illustrative drawings and in the 95 detailed following description based thereon, set out one possible embodiment of the same.

40 In these drawings:

Figure 1 is a side elevation showing the 45 application of the pad, in dotted lines;

Figure 2 is a detail in side elevation of the 50 improved pad; and,

Figure 3 is a transverse section taken on 55 the lines 3—3 of Figure 2 looking in the di- 60 rection in which the arrow points.

Having more particular reference to the 65 drawing, in connection with which like char- 70 acters of reference will designate corre- 75 sponding parts throughout, my improved 80 pad may be stated to comprise a primary 85 shield, guard or pad designated by the nu- 90 meral 1, consisting of a strip of fabric such 95 as is usually employed in the construction 100 of sliding pads of this character having the

upper portion thereof slightly widened as in- 10 dicated at 2 whereby to fully cover the hips 15 of a wearer, while the lower or remaining por- 20 tion of the primary pad is reduced, as indi- 25 cated by the numeral 3 being of a width and 30 length such as will amply shield and protect 35 the upper portion of the legs of a wearer 40 during sliding. The widened upper portion 45 of the primary pad 1 is adapted to be ar- 50 ranged adjacent the inner side of the waist 55 band of the trousers of a baseball player 60 wearer, being fastened thereto in any suit- 65 able manner, while the lower portion of the 70 pad depends from this point of jointure with 75 the trousers of the wearer and is adapted to 80 be snugly engaged with the outer portion of 85 the upper part of the wearer's leg by means 90 of an elastic band or strap 4 secured at its 95 opposite ends to the side or marginal por- 100 tions of said lower portion 3 as indicated in 105 the Figure 3.

A secondary pad 5 is arranged upon the 110 primary pad 1 at a bias to the latter and 115 has the upper marginal portion of the same 120 secured by rows of stitching 6 to the upper 125 or widened portion 2 of said primary pad as 130 clearly shown in the Figure 2, the remainder 135 of the secondary pad being free and movable 140 with relation to the adjacent portion of the 145 primary pad 1; being adapted to hang 150 loosely thereover when the player is in a 155 standing, running or substantially upright 160 position. In this connection, it will be noted 165 that by reason of the biased disposition of 170 the secondary pad 5 upon the primary pad 1 175 that the straight upper marginal portion 180 thereof will be arranged at an incline upon 185 the widened portion 2 of said primary pad 1, 190 but that the curved lower portion 7 of the 195 secondary pad will be permitted to hang or 200 depend from its point of jointure with the 205 primary pad and normally overlie the same.

To ensure free movement of the secondary 210 pad 5 over the lower portion 3 of the pri- 215 mary pad 1, as when a player wearing the 220 same executes a "slide" a covering or shield 225 of leather or similar friction receiving ma- 230 terial 8 is arranged upon that face of the 235 lower portion 3 of the primary 1 adjacent 240 the dependent portion of the secondary pad 245 5 and as will be noted, is of a shape or 250 curvature approximately corresponding to 255 that of the lower portion of said secondary 260 pad 5 for an obvious purpose. The shield 265 8, preferably, is of a size slightly greater 270 than the curved portion of the secondary 275

pad 5 and in consequence, offers ample frictional sliding surface for the same.

The shield 8 may be secured by rows of stitching 9 to the adjacent portion 3 of the primary pad 1 or as will be readily understood, may be secured in various other ways common in the art.

In use of my improved sliding pad, as hereinbefore stated, the lower or free portions of the primary and secondary pads 1 and 5 depend from the waist and hip portions of a wearer, extending downwardly over the hip and upper portion of the leg adjacent which it is worn and likewise adjacent the inner side of the particular trouser leg thereover. When a player executes a "slide" into a base while participating in a game of baseball, the major portion of the stress incident to such "sliding" of the body will be directed onto the secondary pad 5 causing the same to immediately fold or crumple upon itself longitudinally of the primary pad 1 in a direction opposite to the movement of the player's body. By reason of this direction of the major portion of the stress to the secondary pad 5 at the outset of the sliding movement of the body, it will be understood that with the further application of stress to the device, the same would be applied to the primary pad 1, but in a greatly modified form. Because of the fact that the lower portion 3 of the primary pad 1 is secured to the leg of a wearer, the movement of this primary pad materially with respect to the adjacent portion of the leg guarded or shielded is reduced and hence, the forming of painful abrasions or so-called "strawberries" upon the hip and leg portions of such wearer will be prevented. Because of the presence of the anti-frictional shield 8, it will be understood that the crumpling or longitudinal movement of the free portion of the secondary pad 5 over the primary pad 1 will be readily permitted and that such movement of the secondary

pad over the lower portion of the primary pad will not tend to cause the latter to wrinkle or move upwardly or longitudinally over the leg of a wearer and thus expose a portion of the same to the ground during sliding movement of the player's body.

Furthermore, because of the biased arrangement of the secondary pad 5 upon the primary pad 1, said secondary pad will be caused to slide over the anti-frictional shield 8 or covering 8 irrespective of the course or path of travel of the body of a wearer during "sliding" and in consequence, such secondary pad will be permitted, at all times, to receive the initial and major stress of the "slide," irrespective of whether the same is the so-called "hook" slide or "fade-away" slide, wherein the body of the person sliding is distorted by curving of the same and the legs in an endeavor to reach the base and at the same time, elude the baseball in the hands of an opposing player.

Manifestly, the construction shown is capable of considerable modification and such modification as is within the scope of my claim, I consider within the spirit of my invention.

I claim:

In combination with ball player's trousers a stationary primary pad stitched parallel with the upper edge thereof, a secondary pad arranged at a bias to the first mentioned pad and being of less area than same, said secondary pad being stitched at its upper portion to the stationary primary pad and having its lower end and sides free to move in any direction, and a leather shield of an area less than the primary pad and equal to the secondary pad positioned between said pads to facilitate the movements as between the pads.

In witness whereof I have hereunto set my hand.

CLYDE WARES.
